CLAIM

The ornamental design for a jewelry box, as shown and described.

DESCRIPTION

FIG. 1 is a perspective view of the jewelry box showing my new design;

FIG. 2 is a another perspective view of the jewelry box showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof shown in an open environment.

The dash broken lines in the figures illustrate portions of the article that form no part of the claimed design. The dot-dot-dash broken lines in the figures illustrate stitching that forms no part of the claimed design.

1 Claim, 9 Drawing Sheets
